UNITED STATES PATENT OFFICE.

JOHN B. NAINTEAU, OF PAWTUCKET, RHODE ISLAND.

SPINDLE.

1,147,638.

Specification of Letters Patent. Patented July 20, 1915.

Application filed May 21, 1914. Serial No. 840,056.

To all whom it may concern:

Be it known that I, JOHN B. NAINTEAU, a citizen of the United States, residing at Pawtucket, in the county of Providence, 5 State of Rhode Island, have invented certain new and useful Improvements in Spindles; and I do hereby declare the following to be a full, clear, and exact description of the invention, such as will enable others 10 skilled in the art to which it appertains to make and use the same.

This invention relates to spinning frames and has special reference to mountings or bearings for the spindles used in such frames.

15 In the usual spindle mountings oiling is accomplished through an open hole or tube and the amount of oil supplied at one time is thereby necessarily limited. Furthermore, dust and foreign substances can enter the 20 usual oil hole and they not only tend to clog the oil passages but also to injure the spindle.

Another disadvantage incident to the spindle mountings with which I am 25 acquainted, is that under the rapid rotation of the spindle, the oil which has been fed into the space between the usual bolster and the spindle will climb or work its way up the spindle to a point above the spindle 30 mounting, thence dropping or flowing down on top of the mounting so that, not only is the upper exterior portion of the spindle coated with oil, but the mounting is likewise exteriorly so coated, and consequently 35 the band or belt passing around the whirl is liable to be soiled, as is also the arm itself. Furthermore, in the ordinary type of spindle mounting there is employed a tongue or catch which is located at one side of and 40 projects over the top of the whirl, this catch or tongue being usually mounted on top of the oil chamber. The result is that it is in the way of the band or belt which passes around the wheel, and as the belt in its 45 travel is liable to flap or wabble, it strikes against this catch or tongue and consequently is rapidly worn out, so that it is frequently broken.

To obviate the above recited disadvantages incident to the ordinary type of spindle, I propose to provide an oil baffling member, which is carried by the spindle and is located in a small chamber or space between the top of a sleeve surrounding the 55 bolster, so that, as the oil works up the spindle it will strike this baffle and be deflected

downward into the chamber. In other words, by means of this baffle, located in such chamber aforesaid, the oil is prevented working up the spindle above the spindle 60 mounting. I also prevent the wearing or injuring of the band or belt passing over the whirl by locating the oil chamber below the whirl and providing the latter with a cover or top which is devoid of all hooks, 65 clips, tongues or other projections, which are liable to catch or contact with the belt or band passing over the whirl.

Another object of the invention is to provide an improved spindle mounting wherein 70 the oil will be kept in a suitable reservoir or cup so that it may at all times be supplied to the spindle.

A further object of the invention is to provide an improved adjustment for such 75 spindles wherein the spindle may be adjusted and the oil baffling member of the spindle properly located relative to the annular in-turned flange at the top of the sleeve surrounding the spindle without making it necessary to stop the machine. 80

With the above and other objects in view the invention consists in general of certain novel details of construction and combination of parts hereinafter fully described, 85 illustrated in the accompanying drawings, and specifically claimed.

In the accompanying drawings, like characters of reference indicate like parts in the several views, and.—Figure 1 is a vertical 90 section through a portion of a spinning machine showing a spindle mounting constructed in accordance with this invention. Fig. 2 is a plan view of a certain sleeve and oil cap used herewith. Fig. 3 is a vertical median 95 section through such a cap. Fig. 4 is a vertical median section through the cup cap. Fig. 5 is a bottom view of said cap. Fig. 6 is a detail side elevation of the spindle bolster. Fig. 7 is a detail side elevation of the 100 spindle adjusting nut. Fig. 8 is a plan view of a lock nut used herewith. Fig. 9 is a transverse section through said nut. Fig. 10 is an enlarged detail view of a stop pin used herewith. 105

In carrying out the objects of this invention there is provided the usual spindle 1 having the tapering upper end 2 and the tapering lower end 3, the latter constituting the cone foot step bearing for the spindle. Frictionally engaged upon the spindle is a sleeve 4, whereon is formed a whirl 110

5 of the usual type and by means of which the spindle is rotated. Mounted upon said sleeve 4 is a bobbin holding device 6. All of the foregoing parts are preferably of 5 any one of the standard commercial types.

It is to be understood that the usual series of spindles are employed and that the machine is equipped with the usual spindle rail 8. For each of the spindles in the machine there is provided a sleeve 7 which is set into the spindle rail as at 7' and is locked in position in the rail by a suitable nut 7a. Each of these sleeves is provided immediately above the threaded portion with a cylindrical portion 9 and below this threaded portion is a second reduced cylindrical portion 11. Intermediate the length of the spindle and positioned above the rail is a cup 12 which surrounds said sleeve and thus forms an annular oil receiving chamber. The upper end of the sleeve is preferably of less diameter than the portion 9 and extends upward above the cup as indicated at 13. The interior 14 of this portion of the sleeve is likewise of less diameter than the interior 15 of the central portion of said sleeve while the lower end of the sleeve has an opening therein reduced and threaded as at 16. The upper end of said sleeve has its opening also reduced and threaded as at 17. Extending from an annular chamber formed by the cup 12 and communicating with the interior 15 of said sleeve is a plurality of oil ports 18. The cup 12 is likewise provided, near its upper edge with a lateral oil port 19. Beneath the oil port 19 the cup is provided with a threaded recess 20 and opposite said recess the wall of the cup is bored to provide a vertical recess 21. Slidable in the vertical recess 21 is a pin 22 provided with a conical point 22' and beneath the lower end of this pin is a spring 23 which urges the pin upward. The cup 12 is preferably filled with fibrous material 45 as indicated at 24.

Mounted on the cup 12 is the cap 26 having in its top 27 an opening 28 to receive the sleeve 7. This cap is likewise provided with an oil port 29 which may be caused to register with the port 19 by rotation of the cap on the cup and in order to limit the amount of such rotation the cap is provided with a peripheral slot 30 which registers with the recess 20, a screw 32 passing through said slot and engaging the recess so that the cap may be turned to a certain extent in either direction while, at the same time, it cannot be removed from the cup without unscrewing the screw 32. The top 50 of this cap is also provided on its under side with a plurality of spaced conical recesses 31 wherein the point 22' of the pin 22 engages so that the cap may be held either with the ports 19 and 29 in registry or with 55 these ports out of registry. In connection

with this invention there is provided a bolster having cylindrical upper portions 35 adapted to fit the portion 14 of the sleeve. Below this cylindrical portion the bolster is reduced as at 36 and the portions 35 and 36 are provided with a suitable opening or bore 37 wherein the end 3 of the spindle fits closely. The lower end of this bolster is enlarged and threaded as at 38 so that it engages the threaded portion 16 of the sleeve 7 and this lower end is provided with a cylindrical bore 39 for purpose hereinafter to be described. Suitable screw driver slots are also provided in this bolster and oil ports 41 extending laterally through the central portion of said bolster. At 43 is shown the adjusting screw which carries a cylindrical boss 44 forming the foot step bearing for the spindle and this screw is also threaded into the portion 16 of the sleeve 7, being provided with a screw driver slot for the purpose of adjustment. At 47 is shown a lock nut for the adjusting screw and this lock nut is provided with the spanner hole 48 and the threads 49 to engage the threaded portion of the screw 43.

In oiling the device, which may be done while the machine is running, the cap is turned until the ports 19 and 29 are in registry. The nozzle of the oiler is inserted and the cup filled with oil. This oil will pass out through the port 18 and port 41 to the spindle end 3. The adjustment of the device may also be done while the machine is running by loosening the lock nut 47 and turning the screw 43 to the right or left as desired.

By reference to Fig. 1 it will be seen that the upper end of the sleeve is formed with an annular inturned flange producing a reduced threaded opening or bore 17, hereinbefore mentioned, and as this flange, which is indicated at 17', lies spaced from the upper end of the bolster, a small chamber is produced by the flange 17', the top end of the bolster and the portion of the wall of the sleeve lying between the bolster and the flange. The spindle is provided with a collar 55 having internal screw threads running in the same direction as the threads of the flange 17', so that in setting the spindle in operative position the collar may be screwed through the bore 17 at the top of the sleeve until it lies within the chamber formed as aforesaid. This collar performs an important two-fold function. Not only does it prevent the accidental disengagement of the spindle or its bearing, that is to say prevents the spindle from jumping upward, but primarily it acts as an oil baffle. The oil as it is supplied from the oil cup or receptacle, passes through the oil ports or passages 18 to the space between the sleeve and bolster of the spindle and thence through the port 41 to the spindle. In the rapid ro-

tation of the spindle the oil will climb or travel upward thereon, and were it not for this baffling collar 55, such oil would continue it way up the spindle to the exterior of the complete housing, and would not only coat the upper portion of the spindle, but would overflow on the housing and consequently would not only collect dirt and grit, thus soiling the parts, but would be liable 5 to soil the belts passing over the whirls, and also in some cases soil the yarn, as small particles of oil would be liable to be thrown off in the rapid rotation of the spindle. With my construction, however, it is impossible 10 for the oil to escape to the exterior of the housing and to coat the upper portion of the spindle, for it has been found in actual use that the oil will be confined within the housing and will not escape therefrom, as is the 15 case with ordinary spindle housings with which I am acquainted. Thus, I not only save the oil, and maintain the spindle and its bearings in a comparatively clean state, but I also avoid the liability of soiling the work 20 25 and the belts or bands of the whirls. It will be noted that while the collar may be screwed through the bore of the flange at the top of the sleeve to bring it within the chamber, such collar will prevent the upward movement of the spindle and the accidental removal of the same from the sleeve, as the spindle can only be removed by unscrewing the collar through the threaded bore 17. There has thus been provided a 30 35 simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed. 40 45 It will also be observed that this prevents this spindle from being withdrawn during doffing of the bobbins.

Having thus described the invention, what is claimed as new, is:—

50 1. The combination with a spindle and a bolster for receiving the lower portion of the spindle, said bolster having an oil passage leading to the spindle, of a sleeve surrounding the bolster and terminating at its upper end above the bolster, said sleeve having an annular inturned flange whereby a chamber is formed around the spindle between the upper end of the bolster and the flange, means below the chamber for supplying oil to the spindle through the passage in the bolster, and an oil baffling member carried by the spindle and located in the above mentioned chamber for preventing the passage of oil up the spindle past the top of the sleeve. 55 60 65

2. The combination with a spindle and a bolster for receiving the lower portion of the spindle, a sleeve surrounding the bolster and projecting above the upper end of the bolster, means for supplying oil to the spindle at a point below the upper end of the bolster, and an oil baffling member mounted on the spindle and located between the upper end of the bolster and the top portion of the sleeve for preventing the oil passing up the spindle and through the top end of the sleeve. 70 75

3. The combination with a spindle and a bolster for receiving the lower portion of the spindle, a sleeve surrounding the bolster and projecting above the upper end of the bolster, means for supplying oil to the spindle at a point below the upper end of the bolster, an oil baffling member mounted on the spindle and located between the upper end of the bolster and the top portion of the sleeve for preventing the oil passing up the spindle and through the top end of the sleeve, and means carried at the lower end of the bolster and upon which the lower end of the spindle rests, for moving the spindle to adjust the oil baffling member relative to the top end of the sleeve. 80 85 90

4. The combination with a spindle and a bolster for receiving the lower portion of the spindle, said bolster having an oil passage leading to the spindle, of a sleeve surrounding the bolster and projecting at its upper end above the bolster, said sleeve having an inturned flange forming a reduced port through which the spindle passes, said flange forming a chamber in conjunction with the upper end of the spindle and the adjacent wall section of the sleeve, an oil receptacle carried by the sleeve and located below the upper end thereof, said chamber having oil passages for supplying oil to the space between the sleeve and the bolster, and an oil baffling collar carried by the spindle and located in the aforesaid chamber. 95 100 105 110

5. The combination with a spindle having an oil baffling collar mounted thereon, of a bearing for the spindle, a sleeve surrounding the spindle and provided with an inturned flange located above the collar and through which the collar carried by the spindle is passed in setting the spindle in the bearing, and means carried by the sleeve for supplying oil to the bearing and to the spindle at a point below the collar. 115 120

6. The combination with a spindle and a bolster for receiving the lower portion of the spindle, said bolster having an oil passage leading to the spindle, of a sleeve surrounding the bolster and terminating at its upper end above the bolster, the upper end of said sleeve having an annular inturned threaded flange, whereby a chamber is formed around the spindle between the upper end of the bolster and the flange, an oil 125 130

receptacle carried by the sleeve at a point below the chamber and provided with oil passages for carrying oil to the space between the sleeve and the bolster, an ext-
5 riorly threaded oil baffling collar carried by the spindle and adapted to be threaded through the bore of the threaded flange to lie in the aforesaid chamber when the spin-
dle is in operative position, said collar pre-
10 venting the passage of oil up the spindle past the top of the sleeve, and a stud car-
ried at the lower end of the sleeve and upon which the lower end of the spindle is
adapted to rest, said stud being adjustable
15 to adjust the oil baffling collar relative to
the flange at the top of the sleeve.

7. The combination with a spindle, of a
spindle mounting therefor including a
sleeve and an oil cup arranged intermediate
20 of and surrounding the sleeve, said cup hav-
ing an annular wall provided with an oil
inlet port, said cup also having an oil port
leading to the interior of the sleeve, and a
cap having an approximately circular plate-
25 like top wall provided with a central open-
ing for the passage of the sleeve, and an an-
nular flange depending from said top wall
and fitting over the annular wall of the cup,
said cap being loosely fitted to turn on the
30 sleeve and cup and having its annular flange
provided with an oil inlet port adapted to

be turned into and out of register with the
oil port in the annular wall of the cup.

8. The combination with a spindle, of a
spindle housing including a sleeve having a 35
reduced opening through the upper end
thereof, an oil receptacle surrounding the
sleeve, a bolster mounted in the sleeve and
provided with a reduced central portion
40 spaced from the walls of the sleeve to form 45
an annular space, said bolster having oil
ports opening into the space, said receptacle
having oil ports leading to the space be-
tween the bolster and sleeve, and an oil baf-
feling collar carried by the spindle and lo-
cated between the upper end of the bolster
and the top wall of the sleeve.

9. The combination with a spindle, of a
housing including a sleeve through one end
of which the spindle projects, means for 50
supplying oil to the portion of the spindle
surrounded by the sleeve, and means carried
by the spindle for preventing the passage
of oil up the spindle past the top of the
sleeve. 55

In testimony whereof, I affix my signa-
ture, in the presence of two witnesses.

JOHN B. NAINTEAU.
